4 Claims. (Cl. 122—235)

The invention relates to a water-tube boiler. In particular the invention relates to a type of such boilers which comprise tubes extending from a lower distributor to an upper collector, and being exposed to a radiant heat over a portion of their length. Other tubes, bent U-shaped and projecting into the current of the combustion gases, extend from and open again into the first mentioned tubes and are shielded against radiation from the furnace by still other tubular members.

The invention aims to simplify the structure of the mentioned type of boilers and to reduce the space required by heating surfaces whereby, for the same steam output, a substantial saving of material and labor is achieved in comparison to the conventional boilers.

It is another object of the invention to provide a structure whereby through the connection of a larger number of parallel U-shaped, serpentine tubes, a higher cooling effect is obtained. In this respect it has been found that the serpentine tubes will be cooled the more efficiently the greater the amount of steam created in the tube portions which precede the serpentine tubes, inasmuch as thereby the speed of the steam-water mixture will be accelerated and the distribution of the mixture among the U-shaped serpentine tubes, which are connected in parallel, will be improved.

It is still another object of the invention to provide a boiler of the mentioned type in which the U-shaped serpentine tubes, which project into the current of the combustion gases, extend from tubes which screen the serpentine tubes against radiation from the furnace. In such a structure special distributors and collectors become unnecessary for the evaporating heating surfaces connected in succession to the furnace, and the U-shaped serpentine tubes can be arranged horizontally whereby much space is saved in the gas flue. The increased steam production in the heating tubes which precede the serpentine tubes causes a high buoyancy effect which insures a cooling of the serpentine tubes under all conditions of operation.

In order to ensure the water circulation through the U-shaped serpentine tubes, it is furthermore proposed to provide a throttle between the entrances and outlets of the serpentine tubes in the tube from which the serpentine tubes extend. The steam contained in the rising steam-water mixture streams upwards through such throttle whereas the water will be compelled to enter the serpentine tubes. It is of high importance that the openings of the U-shaped serpentine tubes into the tubes from which they project are located below the water level of the separator drum as otherwise the water circulation in the serpentine tubes will be impaired. A further improvement of the water circulation can be obtained by the arrangement of return pipes and/or steam transfer pipes of a kind well known in the art. Such return pipes lead downwards from the collector to the distributor of the tubes which carry the U-shaped serpentine tubes, whereas the

2

steam transfer tubes conduct the steam directly from the collector to the separator drum.

Further objects and details of the invention will be apparent from the description given hereinafter and accompanying drawing illustrating several embodiments thereof by way of example.

In the drawing:

FIG. 1 shows a boiler of the invention in front elevational section on the line I—I in FIG. 2;

10 FIG. 2 is a side-elevational sectional view of the boiler of FIG. 1 taken on the line II—II; and

FIG. 3 shows a detail of the boiler in a sectional plan view taken on line III—III in FIG. 1.

The drawing shows a boiler of the invention having a 15 flue located above the furnace and passed by the combustion gases in a horizontal direction.

20 The water-tube boiler illustrated includes an insulating brickwork shell conventionally shown at 51 in FIG. 2, and has a carrying framework which is formed by vertical downcomers 31, return pipes 31', longitudinal distributors 32, transverse distributors 32' and 32'', longitudinal collectors 33, transverse collector 33' and a drum 34. The front wall and ceiling tubes 35 and the rear wall tubes 36 of the furnace extend from the transverse distributors 32' and 32'', respectively. The furnace is furthermore bounded by groups of juxtaposed vertical side wall tubes 38 and 39 which, over a shorter distance of the length of the furnace, extend straight upwards from the longitudinal distributors 32 to the collectors thereabove.

25 Over the remainder of the length of the furnace there are groups of side wall tubes 38' and 39' which in a plane somewhat higher than half the height of the boiler, are bent approximately horizontal so as to cross the boiler space with portions 38'' and 39'' and to further extend 30 vertically with portions 38''' and 39''' upwards to the collectors 33 on the sides opposite to those on which they are connected to their longitudinal distributors 32. It will be noticed that the tubes 38'' are located each between two tubes 39'' so that in the plane of the bent portions 38'' and 39'' a closed ceiling is formed above which a 35 horizontal flue 55 extends. U-shaped serpentine tubes are arranged in the flue 55 constituting a heating surface 40 in connection with the tube portions 38''' and another heating surface 40' in connection with the tube portions 39''' so that the sets of tubes of the heating surface 40 alternate and interengage with the sets of tubes of the surface 40'. Owing to this arrangement the total length of tubes exposed to radiation is increased and thus the 40 evaporation in these tubes is intensified wherefrom a higher speed of flow results in these tubes and consequently a higher cooling effect. Simultaneously it becomes possible to connect a larger number of serpentine tubes to each side wall tube whereby an important increase of the heating surface in a very relatively small 45 space is obtained. The increase of the length of tubes heated by radiation increases the pumping effect in these tubes.

50 As shown in FIG. 3, a throttling disc 113 having an opening 114 is inserted in the tube portions 38''' and 39''' between the entrances and exits of the serpentine tubes 40 and 40' to divert the flow of fluid from the tube portions 55 to the serpentine tubes.

55 It will be apparent to those skilled in the art that modifications and alterations of the structure illustrated and described can be made without departure from the

essence and spirit of my invention which for that reason shall not be limited but by the scope of the appended claims.

I claim:

1. In a water tube boiler, in combination:

(a) shell means defining a boiler space therein, said shell means having a bottom portion, a top portion, and two horizontally spaced opposite side portions connecting said bottom portion and said top portion;

(b) a distributor system and a collector system respectively mounted on said shell means adjacent said bottom portion and said top portion;

(c) two sets of elongated heating tubes connecting said systems, the tubes of each set being spacedly juxtaposed so as to define interstices therebetween,

(1) each tube having three longitudinally successive portions in said space, the first portions of the tubes of said sets extending upwards from said distributor system adjacent respective side portions of said shell means, a second portion of each tube extending from said first portion thereof horizontally across said boiler space toward the other side portion of said shell means, and a third portion of each tube extending upward from said second portion along said other side portion to connect with said collector system,

(2) the tubes of each set being aligned with the interstices in the other set;

(d) horizontally extending ceiling means dividing said boiler space into a furnace space below said ceiling means and a flue space above said ceiling means, said second tube portions constituting elements of said ceiling means;

(e) a plurality of U-shaped serpentine tubes associated with respective heating tubes of said two sets, said serpentine tubes extending in respective parallel vertical planes in said flue space,

(1) each serpentine tube having an entrance portion and an exit portion, said portions being vertically spaced from each other and connected to the third portion of the associated heating tube,

(2) the serpentine tubes associated with each set of heating tubes being horizontally and vertically offset from the serpentine tubes associated with the other set of heating tubes; and

(f) diverting means in each of said third portions between said entrance and exit portions for diverting fluid from said third portions to the associated serpentine tubes.

2. In a water tube boiler, in combination:

(a) shell means defining a boiler space therein and having a top portion and a bottom portion;

(b) a partition in said boiler space dividing the same into a furnace space and a flue space, said furnace space and said flue space having respective portions communicating with each other, said shell means being formed with a gas discharge port communicating with a portion of said flue space spaced from the portion thereof communicating with said furnace space, said portions of said flue space jointly constituting a path for the flow of gas from said furnace space to said discharge port in a predetermined direction;

(c) a distributor system;

(d) a collector system upwardly spaced from said distributor system, said systems being mounted on said shell means and being separated by at least a portion of said boiler space;

(e) a first set and a second set of juxtaposed heating tubes extending upwards in said boiler space from respective horizontally spaced portions of said distributor system,

(1) a first group of juxtaposed heating tubes in each set extending continuously upwards from

said distributor system to said collector system, (2) the tubes of a second group of juxtaposed heating tubes in each set having each three longitudinally consecutive portions,

(3) a first portion extending upward from said distributing system,

(4) a second portion extending horizontally across said furnace space toward the first portions of the tubes of the second group in the other set, and

(5) a third portion extending upward from said second portion to connect with said distributor system,

(6) the second portions of both sets being juxtaposed to constitute said partition;

(f) a plurality of U-shaped serpentine tubes in said flue space, said serpentine tubes each extending in a respective vertical plane and having two end portions vertically spaced from each other and connected to a respective one of said third portions; and

(g) diverting means in each of said third portions between the end portions of the connected serpentine tube for diverting fluid from said heating tubes to said serpentine tubes.

3. In a boiler as set forth in claim 2, each serpentine tube connected to the third portion of a heater tube of one set being horizontally interposed between two serpentine tubes connected to the third portions of heater tubes of the other set.

4. In a water tube boiler, in combination:

(a) shell means defining a boiler space therein and having a top portion and a bottom portion;

(b) a partition in said boiler space dividing the same into a furnace space and a flue space, said furnace space and said flue space having respective portions communicating with each other, said shell means being formed with a gas discharge port communicating with a portion of said flue space spaced from the portion thereof communicating with said furnace space, said portions of said flue space jointly constituting a path for the flow of gas from said furnace space to said discharge port in a predetermined direction;

(c) a distributor system;

(d) a collector system upwardly spaced from said distributor system, said systems being mounted on said shell means and being separated by at least a portion of said boiler space;

(e) a first set and a second set of juxtaposed heating tubes extending upwards from respective horizontally spaced portions of said distributor system, the sets being spacedly opposite each other,

(1) the tubes in each set having each three longitudinally consecutive portions,

(2) a first portion extending upward from said distributing system,

(3) a second portion extending horizontally from said first portion toward the first portions of the other set, and

(4) a third portion extending upwards from said second portion to connect with said collector system,

(5) said second portions of said heating tubes of one set being vertically offset from the second portions of the heating tubes of the other set, said second portions jointly constituting said partition and being spaced from each other for communication between said furnace space and said flue space through said partition;

(f) a plurality of U-shaped serpentine tubes in said flue space, said tubes each extending in a vertical plane and having two end portions vertically spaced from each other and connected to a respective one of said third portions; and

(g) diverting means in each of said third portions between the end portions of the connected serpentine tube for diverting fluid from said heating tubes to said serpentine tubes.
